UNITED STATES PATENT OFFICE.

GEORGE E. BISHOP, OF CLEVELAND, OHIO.

EYELET FOR FASTENERS.

1,326,637.

Specification of Letters Patent. Patented Dec. 30, 1919.

Application filed September 5, 1917. Serial No. 189,830.

To all whom it may concern:

Be it known that I, GEORGE E. BISHOP, a citizen of the United States, resident of Cleveland, county of Cuyahoga, and State 5 of Ohio, have invented new and useful Improvements in Eyelets for Fasteners, of which the following is a specification, the principle of the invention being herein explained and the best mode in which I have 10 contemplated applying that principle, so as to distinguish it from other inventions.

My invention relates to fasteners and particularly to new and improved means embodied in the eyelet portions thereof. More 15 particularly, my invention relates to new and improved eyelets for use in fasteners designed for securing automobile curtains. My invention is designed to provide a spring or pliable eyelet which will accommodate itself to the various irregularities of the fastener stud and thereby provide an efficient anti-rattler. This is accomplished by the eyelet adapting itself to the fastener stud in all relative positions of 20 the eyelet and stud but not by the eyelet gripping the stud for the purpose of locking the fastener. I have designed this new and improved eyelet particularly for use with that desirable form of stud or button known 25 as the "turning-head" or "turn-button" type but, as mentioned above, the design is not meant to securely lock the fastener stud without the use of the usual locking means, which is, in the type of button to which this eyelet is best adapted, the turning-head, but is designed to provide close adaptation of 30 the eyelet to the stud.

The annexed drawing and the following description set forth in detail certain means 40 embodying my invention, the disclosed means, however, constituting but one of various mechanical forms in which the principle of the invention may be employed.

In said annexed drawing:

Figure 1 represents, upon an enlarged scale, a longitudinal sectional view partially in elevation of my improved eyelet in use with a stud of the turn-button type, the whole shown in use with an automobile curtain; Fig. 2 represents an elevation, from the front of the curtain fabric, of the elements shown in Fig. 1; Fig. 3 represents an elevation from the rear of the curtain fab- 50 ric; Fig. 4 represents a front elevation of a washer forming one of the elements of my 55 improved eyelet; Fig. 5 represents a longitudinal section taken in the plane indicated by the line V—V, Fig. 4; Fig. 6 represents a rear elevation of said washer; Figs. 7, 8 and 9 represent, respectively, sections taken 60 in the planes indicated by the lines VII—VII, VIII—VIII and IX—IX, Fig. 4; and Fig. 10 represents an elevation of a stamped blank before the same is turned up into its final form as a complete washer. 65

In said annexed drawing, 1 represents said washer, being an elliptical shaped ring, more particularly hereinafter described, the same being shown secured to the under side of an automobile curtain fabric 2 by means 70 of the prongs 3 of an ordinary gromet 4, as plainly shown in Figs. 1, 2 and 3. Said eyelet 1 is formed with two oppositely disposed spring-sections 5 adapted to receive a button and adapt themselves to the body 75 thereof, as plainly indicated in the drawing and as hereinafter more fully described. The blank from which said washer 1 is formed is stamped to form slots 6 to receive the prongs 3 of the gromet 4; slots 7, the 80 purpose of which will be hereinafter more fully explained; and a central slot 8 serving to provide the ordinary eyelet opening, all as plainly shown in Fig. 10. Also as plainly shown in said figure, said blank is formed 85 with a number of sets of transverse cuts 9, there being four of such sets and two cuts to a set. The stamped blank, as it appears in Fig. 10, is formed up with the spring elements 5 to complete the washer. Said spring 90 elements 5 consist in the depressed spring end portions 10 disposed intermediately each pair of transverse cuts 9, and the transversely extending portions consisting of the relatively shallow central part 11 and the 95 relatively high end parts 12. Said end parts 12 are turned outwardly to such a depth that the bottom of said outwardly turned parts lie substantially in the same horizontal plane as the top of the central parts 11, 100 as plainly shown by the line A—B, Fig. 5, said line A—B lying in the periphery of one ellipse, whereas the top of the outwardly turned ends 13 lie in the periphery of a second, larger and surrounding ellipse. 105

The above-described eyelet is adapted for

use with any form of stud or button but the turning-head type, shown at 14, in Fig. 1, I have found preferable for use with the same. This button 14 is secured at its base to the 5 frame 15 of an automobile body.

As will be readily understood from the foregoing description, when my improved eyelet is forced over the body 16 of the button 14, the two spring sections 5 are pressed 10 outwardly and accommodate themselves to the sides of the body 16, thus forming an efficient anti-rattler.

It has been found by the use of fasteners heretofore known, in which a button of the 15 general type shown in Fig. 1 has been used, if the stud has not been carefully finished and, sometimes for other reasons, upon the removal of the eyelet from the button, portions of the eyelet, usually the spring portions 20, will catch upon the bottom of the button head and thus render the removal of the eyelet from the button exceedingly annoying and troublesome. The construction which I have designed as an efficient anti- 25 rattler and which has been hereinbefore described and is plainly shown in the accompanying drawing, also obviates this last-mentioned difficulty and annoyance, inasmuch as, by the provision of the outwardly 30 bent ends 13 of the spring sections 5, the portions of the ends 12 which contact with the body of the button 14 lie below the bottom horizontal plane of the outwardly bent parts 13, Fig. 8. In fact, the upper contact- 35 ing line of the ends 12 is designed to be a continuation of, and in the same horizontal plane with, the upper contacting line of the central depressed parts 11 of the spring sections 5, all as is plainly shown in the 40 drawings and particularly by the dotted line A—B, Fig. 5. It is readily apparent that this construction throws the ends 13 of the spring sections 5, when said ends are about to pass over the bottom of the head of the 45 button 14, outwardly from the edges of the bottom of said head with which they might catch, and thus effect such a clearance as to obviate any danger of such interference. A further advantage of my improved eyelet 50 results from the fact that the spring sections 5 and the elliptical curve shown assist in throwing the button 14 out from the eyelet when a separation of the button from the eyelet is started.

55 What I claim is:

1. A button fastener comprising, a member having a body and a head rotatably mounted thereon; and an eyelet comprising a gromet surrounding said body, said head interlocking with said gromet against withdrawal therefrom in a predetermined position of rotative adjustment, and a spring plate adapted to intersect the gromet opening, be displaced by said body, and affording, for anti-rattling purposes, a close

adaptation of the eyelet to the body member in all relative positions of said eyelet and member.

2. A button fastener comprising, a member having a body and a head rotatably 70 mounted thereon; and an eyelet comprising a gromet surrounding said body, said head interlocking with said gromet against withdrawal therefrom in a predetermined position of rotative adjustment, and a resilient washer adapted to intersect the gromet opening, be displaced by said body, and affording, for anti-rattling purposes, a close 75 adaptation of the eyelet to the body member in all relative positions of said eyelet and member.

3. A button fastener comprising, a member having a body and a head rotatably mounted thereon; and an eyelet comprising a gromet surrounding said body, said head interlocking with said gromet against withdrawal therefrom in a predetermined position of rotative adjustment, and a pair of oppositely disposed spring elements adapted 80 to intersect the gromet opening, be displaced by said body and affording, for anti-rattling 85 purposes, a close adaptation of the eyelet to the body member in all relative positions of said eyelet and member.

4. A button fastener comprising, a member having a body and a head rotatably mounted thereon; and an eyelet comprising a gromet surrounding said body, said head interlocking with said gromet against withdrawal therefrom in a predetermined position of rotative adjustment, and one or more 95 spring elements lying in the periphery of an ellipse and adapted to intersect the gromet opening, be displaced by said body, and affording, for anti-rattling purposes, a close 100 adaptation of the eyelet to the body member in all relative positions of said eyelet and member.

5. In an improved eyelet for fasteners, a body portion formed with an eyelet opening 110 and a transversely extending spring element disposed to intersect said opening and comprising a part formed to lie in the periphery of an ellipse and a part formed to lie in the periphery of a second, larger and surrounding ellipse.

6. In an improved eyelet for fasteners, a body portion formed with an eyelet opening and a transversely extending spring element disposed to intersect said opening, said element being formed with relatively high end parts and a relatively shallow central part, said end parts being turned outwardly relatively to the general direction of the spring element proper.

7. A button fastener comprising a member having a body and a head rotatably mounted thereon, and an eyelet co-operating therewith and adapted to encircle said body, said eyelet having an interior, discontinuous surface

presented toward said body, segmental portions of said surface being curved to provide opposed resilient tongues adapted to grip said body and said head interlocking 5 with said eyelet against withdrawal therefrom in a predetermined position of rotative adjustment.

8. A button fastener comprising a member having a body and a head rotatably mounted 10 thereon, and an eyelet coöperating therewith and adapted to encircle said body, said eyelet presenting one or more spring portions to bear on and be displaced substantially radially by said body and said head interlocking with said eyelet against withdrawal therefrom in a predetermined position of rotative adjustment.

9. A button fastener comprising a member having a body and a head rotatably mounted 15 thereon, and eyelet means coöperating therewith, adapted to encircle said body, and

comprising curved spring segments adapted to grip said body and a gromet formed with an eyelet opening, said segments intersecting said opening and said head interlocking 25 with said eyelet against withdrawal therefrom in a predetermined position of rotative adjustment.

10. A button fastener comprising a member having a body and a head rotatably 30 mounted thereon, and an eyelet coöperating therewith and adapted to encircle said body, said eyelet having slits formed in the body thereof, intersecting the eyelet opening, and providing one or more spring segments 35 adapted to be displaced by said body, said head interlocking with said eyelet against withdrawal therefrom in a predetermined position of rotative adjustment.

Signed by me, this 29th day of August, 40
1917.

GEORGE E. BISHOP.
